UNITED STATES PATENT OFFICE.

WILLIAM T. WILKINSON, OF LINDSAY, CALIFORNIA.

WASHING-MACHINE.

1,203,440.

Specification of Letters Patent. Patented Oct. 31, 1916.

Application filed February 16, 1916. Serial No. 78,723.

To all whom it may concern:

Be it known that I, WILLIAM T. WILKINSON, a citizen of the United States, residing at Lindsay, in the county of Tulare and State of California, have invented certain new and useful Improvements in Washing-Machines, of which the following is a specification.

This invention relates to a washing machine of the barrel type and the principal object of the invention is to provide a washing machine having an improved type of clothes compressor forming part thereof, the clothes pounder and the inner cylinder in which the clothes pounder is mounted being formed of corrugated metal so that the clothes will be thoroughly acted upon while in the washing machine and easily and quickly cleaned.

Another object of the invention is to provide improved means for mounting the inner and outer receptacles and also improved actuating means for the washing machine.

Another object of the invention is to so construct this washing machine that it will be strong and durable and also to so construct it that it will be comparatively simple in construction and not liable to easily get out of order or need repair.

This invention is illustrated in the accompanying drawings, wherein:—

Figure 1 is a vertical transverse view through the improved washing machine. Fig. 2 is a view showing the receptacles and inner cylinder in longitudinal vertical section and the remainder of the machine in elevation.

The supporting structure consists of the two end standards 10 and which are carried by the cross bars 11 and braced by the inner and outer braces 12 and 13. These standards are positioned in spaced relation and are provided with bearings through which extend the stub axles 14 and 15, the axles 45 extending through the head 16 of the barrel 17 and terminating at their inner ends in disks 18 connected with the head of the cylinder 19.

From an inspection of Fig. 1 it will be readily seen that the barrel or outer receptacle 17 is constructed of staves in the manner usually used when constructing barrels whereas the inner receptacle or cylinder 19 is formed of corrugated sheet metal. The operating cylinder 20 which is mounted within the cylinder 19 is also formed of

corrugated sheet metal, the receptacle 19 and cylinder 20 being provided with openings 21 and 22 so that water can freely circulate through the same. Closures 23 and 24 are 60 provided for the outer and inner receptacles 17 and 19 and are releasably held in place by the bolts and wing nuts 25 and 26. These inlets are in alinement as clearly shown in Fig. 1 so that access to the interior to the 65 inner receptacle can be easily had.

When assembling this washer, the stub shafts are first connected with the heads of the inner receptacle 19 through the medium of the bolts or rivets 27 and after the operating cylinder 20 has been put in place the heads of the inner cylinder are connected with the corrugated walls thereof. The stub shafts 14 can then be passed through the bearings in the head of the barrel or outer receptacle 17 and 70 the second head then placed upon the stub shaft 15 and the securing hoop 28 put in place. The stub shafts are then passed through suitable bearings formed in the standards 10 after which the small gear 29 75 will be placed upon the outer end of stub shaft 14 and the fly wheels 30 can be placed upon the outer end portion of stub shaft 15. This small gear wheel 29 meshes with the large driving gear 31 which is rotated 80 through the medium of the lever 32 mounted upon the supporting pin 33 and connected with the driving gear 31 by means of links 34. By oscillating the lever 32, the driving gear 31 can be rotated and this will rotate 90 gear 29 rigidly mounted upon stub shaft 14. The inner and outer receptacles will be rotated as the shafts 15 are secured to the inner receptacle and the outer receptacle is held rigid upon the shafts, and as these receptacles rotate the operating cylinder 20 will travel about within the inner receptacle. The clothes are placed within the inner receptacle and after the water is in place, the two closures 23 and 24 are secured. As the 95 machine is rotated the operating cylinder 20 will rotate and travel about within the inner receptacle 19 and not only keep the water and clothes in motion but will also press the clothes against the walls of the inner receptacle.

A bracket 35 has been provided so that a wringer may be mounted where it will be convenient for use when removing the clothes. After the clothes have been removed the receptacle can be turned so that 100 the water can flow out through the inlet openings of the receptacles. 105 110

I have therefore provided a washing machine which will operate very efficiently and which is very simple in construction, easy to assemble and inexpensive to manufacture and operate.

What is claimed is:—

1. A washing machine comprising supporting standards, a water receptacle positioned between said standards, a perforated clothes receptacle mounted within said water receptacle, stub shafts connected with said clothes receptacle and passing through the heads of said water receptacle and rotatably supported by said supporting means, the water receptacle being fastened upon said stub shafts and turning with the clothes receptacle, an operating cylinder mounted within said clothes receptacle and freely movable within the clothes receptacle, and means for rotating one of said stub shafts to rotate said clothes and water receptacles.
2. A washing machine comprising sup-

porting means, a water receptacle, a clothes receptacle positioned within said water receptacle and formed of perforated material having longitudinally extending corrugations, stub shafts extending from said clothes receptacle through said water receptacle and rotatably supported by said supporting means, said water receptacle being rigidly mounted upon said stub shafts, a perforated operating cylinder formed of sheet material having longitudinally extending corrugations mounted in said clothes receptacle and freely movable therein, and means connected with one of said stub shafts for rotating the same.

In testimony whereof I affix my signature in presence of two witnesses.

WILLIAM T. WILKINSON.
